Primary Examiner — Kevin K Rudzinski*Assistant Examiner* — Clare Ann Gannon(74) *Attorney, Agent, or Firm* — Quickpatents, LLC;
Kevin Prince(57) **CLAIM**

I claim the ornamental design for a wand for blinds, as shown and described.

DESCRIPTION

FIG. 1 is a perspective view of a wand for blinds, showing a first embodiment of my new design;

FIG. 2 is a front elevational view of FIG. 1, the rear elevational view being a mirror image thereof;

FIG. 3 is a left-side elevational view of FIG. 1, the right-side elevational view being a mirror image thereof;

FIG. 4 is a top plan view of FIG. 1;

FIG. 5 is a bottom plan view of FIG. 1;

FIG. 6 is a perspective view of a second embodiment thereof;

FIG. 7 is a right-side elevational view of FIG. 6;

FIG. 8 is a left-side elevational view of FIG. 6;

FIG. 9 is a rear elevational view of FIG. 6;

FIG. 10 is a front elevational view of FIG. 6;

FIG. 11 is a top plan view of FIG. 6; and,

FIG. 12 is a bottom plan view of FIG. 6.

The broken lines in the figures depict portions of the wand for blinds that form no part of the claimed design.
